(57) **CLAIM**

The ornamental design for a cat climber as shown and described.

DESCRIPTION

FIG. 1 is a perspective view of a cat climber;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is an enlarged view of portion 8 shown in FIG. 7.
The broken lines in the figures illustrate portions of the cat climber that form no part of the claimed design.
